OF ILLINOIS.

MULTIPLE-SPINDLE DRILL-HEAD.

1,164,813.

Specification of Letters Patent.

Patented Dec. 21, 1915.

Application filed April 15, 1914. Serial No. 831,893.

To all whom it may concern:

Be it known that we, FREDERICK W. HOEFER and CHESTER A. HOEFER, residing at Freeport, in the county of Stephenson and State of Illinois, have jointly invented certain new and useful Improvements in Multiple-Spindle Drill-Heads, of which the following is a specification.

Our invention relates to certain improvements in multiple spindle drill heads.

Devices of the class to which this invention belongs are designed to be attached to the spindle sleeve of a single spindle drill press and to convert the same into a double spindle drill press, the two spindles of which are adjustable toward or from each other so as to bore two holes at once at any desired distance apart. In this art it is common to provide an extension of the drill press spindle having a master gear fast thereon, a housing or casing having suitable bearings, adjustable swinging arms vertically pivoted to the casing and carrying drill spindles provided with driving pinions, and suitable gearing connecting the master gear with the respective gears upon the drill spindles. The space which can be conveniently appropriated for these auxiliary heads is necessarily limited, and in fact the more compact they can be made the more convenient they become and the wider the range of work to which they are adapted.

It is the purpose of this invention to so construct and arrange the various necessary elements of one of these devices as to provide a stout, compact structure having the widest possible range of adjustment within the least space that is consistent with strength and satisfactory operation.

To such end the invention consists in various novel characteristics that will be fully brought out in the following description and the essential portions of which will be definitely stated in the claims.

In these drawings Figure 1 is a front elevation of a complete head; Fig. 2 is a top plan of the same, showing the adjustable arms in one of their alternative positions by means of dotted lines; Fig. 3 is a vertical section in the line 3-3 of Fig. 2 looking in the direction of the arrow 3; Fig. 4 is an under plan of Fig. 1; Fig. 5 is an elevation of the lower portion of the cylindrical part of the case which clamps upon the spindle sleeve of the drill press, affords a bearing

for the extension of the drill spindle and also bears a reduced downward extension to which the remaining portions of the casing are secured; Figs. 6, 7 and 8 are similar elevations of other portions of the casing which are secured to and relatively stationary with regard to said cylindrical part; Figs. 9, 10 and 11 are top plans of said other portions of the casing; Figs. 12 and 13 are elevations of the two parts of one of the swinging arms, carrying adjustable spindles, and Figs. 14 and 15 are plan views of the same.

Referring to these drawings A is a cylindrical auxiliary sleeve split upon the rear side at the top, a , and provided with a clamping screw, a^1 , by means of which it is intended to be firmly clamped upon the spindle sleeve of the drill press. At the lower end is a reduced extension, a^2 , adapted to enter and support the parts of the casing below the same. The interior of the cylindrical sleeve is bored to form a bearing for an extension of the drill press spindle which is seen in Fig. 3 at z and upon the lower portion of which is the master gear Z of the head. In the complete device this master gear drives two loose gears upon opposite sides thereof of which one is shown at Y in Fig. 3 and as the two are precisely similar in form and arrangement both need not be described in detail. These loose gears are in mesh with pinions X upon the adjustable spindles W . To provide a casing to accommodate these gears and in which they can be conveniently placed in assembling the device we construct the same in three parts, of which the lower, B, Figs. 8 and 11, is of irregular cup shape having a large bore, b , of proper size to receive the master gear, and two smaller bores, b^1 , b^2 , corresponding in size to the loose gears Y . The bottom plate of the cup is bored at b^3 , b^4 , b^5 , concentric with the larger bores to provide bearings for the lower end of the spindle extension and for two pins or bolts upon which the loose gears are mounted. The cup B also has four holes, b^6 , b^7 , b^8 and b^9 , to receive screws by means of which it is secured to the part of the casing next above it. This part C illustrated in Figs. 7 and 10 has a lower plate shaped portion, c , fitted to the top of the cup B and having two bores, c^1 , c^2 , corresponding to b^5 , b^4 , of the cup and a third bore, c^3 , concentric with b of the cup but of a diameter equal to that of the reduced ex-

tension a^2 of the cylindrical auxiliary sleeve A. The part C also has an upward extension, c^4 , surrounding the bore c^3 , provided with three screw threaded holes, c^5 , c^6 , c^7 .
 5 The lower plate portion has four screw threaded holes, c^8 , c^9 , c^{10} , c^{11} to receive the screws which enter through the perforations b^6 , b^7 , b^8 , and b^9 of the cup B.

A plate, D, Figs. 6 and 9, is fitted to the
 10 upper portion of the extension c^4 , and has three perforations, d , d^1 , d^2 , through which the screws pass which turn into the holes c^5 , c^6 , c^7 , and a central perforation, d^3 , registering with the perforations c^3 and adapted
 15 to receive the reduced extension a^2 of the cylindrical sleeve A. The plate D is extended over the bores c^1 , c^2 , of the part C and has screw threaded perforations, d^4 , d^5 , concentric with the same to receive the
 20 threaded ends of cup bolts, the other ends of which are held in the perforations b^4 , b^5 , of the cup B. It should be noted that the bores b^1 , b^2 of the cup B open into the bore b of the same so that the gears for which
 25 these bores are provided may mesh with the master gear located in the bore b .

The swinging arms of the device are made up of two parts shown in Figs. 12 to 15. A U shaped portion, E, has an upright part, e , furnishing a bearing, e^8 , for an adjustable spindle, W, and is enlarged at e^1 to accommodate one of the driving pinions thereof, X. This enlarged portion is extended laterally at e^2 and has a vertically bored recess e^3 , to fit over the upper end of the loose gear Y. The lower portion of the arm is also extended laterally at e^4 and has a perforation, e^5 , seen in Fig. 15, corresponding to perforations b^5 of the part
 35 B and arranged contiguous thereto and to register therewith when the device is assembled. The other part, F, is in the form of a cap or cover for the enlargement e^1 and its lateral extension and has an inverted
 40 cup shaped portion, f , to accommodate a vertical thrust bearing which is seen at V in Fig. 3, concentric with which is a bore, f^1 , which receives the upper end of the adjustable spindle W and affords a bearing therefor. A lateral plate like extension, f^2 , covers the extension of the swinging arm and is perforated at f^3 to receive the upper end of a bolt, U, which also extends through the
 45 perforations, e^5 , Fig. 15, b^5 , Fig. 11, and d^4 , Fig. 9 and is screw threaded in the last and furnishes the pivot upon which the swinging arm is hinged.

The upper face of the swinging arm E is bored and threaded at e^7 , e^8 , e^9 and the cap
 50 F is perforated at f^4 , f^5 , f^6 to register therewith and accommodate the screws by means of which the cap is secured to the swinging arm.

In assembling the head the spindle extension with its master gear is placed in po-

sition in the cup B, the lower end of the spindle extending through the perforation b^5 , which affords a bearing therefor. The part C is slipped over the spindle extension, the perforation c^3 receiving the latter, and the two parts are secured together by means of screws in the holes provided therefor, which have already been described and which bring the bores c^1 , c^2 , into register with the bores b^1 , b^2 . The part E of the
 70 swinging arm is then slipped into position with the hole e^5 , Fig. 15, in line with the hole b^5 , Fig. 11, and the bore e^5 , Fig. 15, in register with the bore c^1 , Fig. 10. The intermediate gear Y is then dropped into these
 75 two bores in mesh at its lower end with the master gear and the adjustable spindle W with its pinion X and its thrust bearing V is inserted in the upright portion of the
 80 swinging arm. The cap F is then placed upon the swinging arm and secured thereon by means of the screws in the screw holes already described. The plate D is now fastened upon the part C by means of the
 85 screws provided therefor and the bolt W inserted and screwed into position. The reduced portion a^2 of the cylindrical auxiliary spindle sleeve A is now forced downward into the bores d^3 , c^3 , and secured therein by an ordinary set screw, not shown in
 90 any of the figures. This completes the casing for the working parts of the device in exceedingly compact and durable form and at the same time affords an easy method of
 95 assembling and securing the parts together. 100

For the purpose of securely fastening the adjustable spindle in any desired position we provide upon the bottom of the part B a plate, G, perforated at g , g^1 , to receive the lower ends of the screw bolts U and be positioned thereby upon the bottom of the part B. Said plate is provided with slots, g^2 , g^3 , arc shaped about these bolts and the lower end of the upright portion, e , of the arm E has a downward extension, e^{10} , screw
 105 threaded, which extends through this slot and carries below the same a nut, H, which may be screwed up upon the plate to clamp the spindle in any desired position.

We realize the possibility of more or less variation in exact form, construction and arrangement of the various parts herein described and therefore it is not our intention to limit ourselves to the specific construction shown but in the following claims we will point out the characteristic features which we consider essential to our invention and in these claims it is our intention to cover all of the patentable novelty contained in our invention over the prior art. 115

We claim as new and desire to secure by Letters Patent:

1. The combination with a main casing containing a spindle extension and a master gear fast thereon, of a second gear engaging 130

the master gear and extending upwardly from its plane, a second arm-like casing inclosing the upper portion of the second gear and swinging about the axis of the latter, a drill spindle mounted in the free end portion of the arm-like casing, and a third gear fast to the drill spindle and engaging the second gear.

2. The combination with a spindle extension bearing a fast gear engaged with duplicate gears at different points, a casing peripherally inclosing the three gears, two arm-like casings above and overlapping the first casing and swinging about the axes of said duplicate gears, respectively, drill spindles mounted in the free ends of the arm-like casings, respectively, and gears inclosed in the arm-like casings, respectively and transmitting movement from the duplicate gears to the corresponding drill spindles.

3. In a device of the class described a sleeve adapted to be clamped to the spindle sleeve of a drill press, a casing upon the lower end thereof, a spindle extension journaled in said casing, a master gear fast on said extension and inclosed in said casing, a swinging arm hinged to said casing, having a drill spindle journaled therein and a downward extension from the bottom thereof, a pinion on said drill spindle, gearing between said pinion and said master gear arranged upon the axis of the swinging arm,

a plate secured to the bottom of the casing and having a slot arc shaped about the axis of said swinging arm to accommodate the extension upon the bottom thereof and a nut screw threaded to said extension and adapted to be clamped upon said plate to secure said arm in any desired adjustment.

4. The combination with a spindle extension having near its lower end a fast gear, of two elongated secondary gears, at a suitable angular distance apart, engaged with the gear first mentioned, a casing peripherally inclosing the first gear and the lower portion of both secondary gears, two arm-like casings inclosing the upper ends, respectively, of the secondary gears, swinging about the axes of the latter and overlapping the main casing, and drill spindles mounted in the free end portions of said arm-like casings respectively, and each bearing within its casing a fast pinion in engagement with the corresponding secondary gear.

In witness whereof we have signed the above application for Letters Patent at Freeport, Illinois, this 24th day of March A. D. 1914.

FREDERICK W. HOEFER.
CHESTER A. HOEFER.
